United States Patent Office

Des. 227,358
Patented June 19, 1973

227,358

RACING VEHICLE

Robert S. Kachler, 1047 Pine Ave.,
Long Beach, Calif. 90813

Filed Mar. 3, 1971, Ser. No. 120,803

Term of patent 14 years

Int. Cl. D12—08

U.S. Cl. D14—3 G

FIG. 4

FIG. 5

FIG. 1 is a perspective view of a racing vehicle showing my new design;

FIG. 2 is a front elevational view thereof;

FIG. 3 is a rear elevational view thereof;

FIG. 4 is a top plan view thereof; and

FIG. 5 is a right side elevational view thereof, the left side elevational view thereof being a mirror image.

I claim:

The ornamental design for a racing vehicle, substantially as shown and described.
